CLAIM

The ornamental design for a ground fault circuit interrupter receptacle with nightlight, as shown and described.

DESCRIPTION

FIG. 1 is a side perspective view of a GFCI receptacle with nightlight, showing my new design;

FIG. 2 is a front elevation view of the GFCI receptacle with nightlight of FIG. 1;

FIG. 3 is a back elevation view of the GFCI receptacle with nightlight of FIG. 1;

FIG. 4 is a left-side elevation view of the GFCI receptacle with nightlight of FIG. 1;

FIG. 5 is a right-side elevation view of the GFCI receptacle with nightlight of FIG. 1;

FIG. 6 is a top elevation view of the GFCI receptacle with nightlight of FIG. 1; and,

FIG. 7 is a bottom elevation view of the GFCI receptacle with nightlight of FIG. 1.

The broken lines shown represent unclaimed subject matter and form no part of the claimed design.
